CLAIM

I claim the ornamental design for a rotatable cutting bit, as shown and described.

DESCRIPTION

FIG. 1 is a front view of the new design, in accordance with an aspect of the invention.

FIG. 2 is a right side view of the rotatable cutting bit of FIG. 1, wherein the left side is identical and omitted as being duplicative of FIG. 2.

FIG. 3 is a back view of the rotatable cutting bit of the invention.

FIG. 4 is a bottom view of the rotatable cutting bit of the invention; and,

FIG. 5 is a top view of the rotatable cutting bit of the invention.

The broken lines shown in the drawings depict unclaimed subject matter and are provided for the purpose of showing environment only.
